UNITED STATES PATENT OFFICE

120,158

DESIGN FOR A BOX

John Marshall Gleason, Marblehead, Mass., assignor to W. F. Schrafft & Sons Corporation, Boston, Mass., a corporation of Massachusetts

Application February 1, 1940, Serial No. 89,939

Term of patent 14 years

To all whom it may concern:

Be it known that John Marshall Gleason, a citizen of the United States, residing at 16 Coolidge Road, Marblehead, Massachusetts, has invented a new, original, and ornamental Design for a Box, of which the following is a specification, reference being had to the accompanying drawing, forming part thereof.

Fig. 1 is a top plan view of a box, showing the new design;

Fig. 2 is a side elevational view thereof; and Fig. 3 is a front elevational view thereof.

The two sides of the box are identical and the front and back of the box are identical.

What is claimed is:

The ornamental design for a box, as shown and described.

JOHN MARSHALL GLEASON.
